(57) **CLAIM**

The ornamental design for a body of a camera for medical use, as shown and described.

DESCRIPTION

FIG. 1 is a perspective view of a body of a camera for medical use, showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is an enlarged end view thereof, taken along line 8-8 in FIG. 4 with its internal mechanisms omitted;

FIG. 9 is an enlarged view of a portion 9 of FIG. 2; and, FIG. 10 is an end view taken along lines 10-10 of FIG. 9 with its internal mechanisms omitted, to better illustrate the contour thereof.

The evenly segmented broken lines indicate portions of the article that from no part of the claimed design. The dash dot dash broken lines indicate cutoff boundaries for enlarged detailed portion views.
